CLAIM

The ornamental design for a cable trough lip, as shown and described.

DESCRIPTION

FIG. 1 is a left-side perspective view of a cable trough lip. FIG. 2 is a right-side perspective view of the cable trough lip.

FIG. 3 is a front view of the cable trough lip of FIG. 1. FIG. 4 is a back view of the cable trough lip of FIG. 1. FIG. 5 is a right-side view of the cable trough lip of FIG. 1. FIG. 6 is a left-side view of the cable trough lip of FIG. 1. FIG. 7 is a top view of the cable trough lip of FIG. 1; and, FIG. 8 is a bottom view of the cable trough lip of FIG. 1. The dashed broken lines depict portions of the cable trough lip which form no part of the claimed design. The dot-dashed broken lines represent boundaries of the claimed cable trough lip and form no part of the claimed design.
